UNITED STATES PATENT OFFICE.

MICHAEL KELLY, OF BUFFALO, NEW YORK.

BOILER.

No. 920,153.

Specification of Letters Patent.

Patented May 4, 1909.

Application filed October 31, 1908. Serial No. 460,486.

To all whom it may concern:

Be it known that I, MICHAEL KELLY, a citizen of the United States, residing at Buffalo, in the county of Erie and State of New York, have invented a new and useful Improvement in Boilers, of which the following is a specification.

The object of this invention is to provide a water heater or steam boiler which enables a greater heating effect of the fuel to be obtained for rapidly and economically heating the water or producing steam.

In the accompanying drawings: Figure 1 is a vertical transverse section of a boiler embodying my invention. Fig. 2 is a vertical longitudinal section in the correspondingly numbered line in Fig. 1. Fig. 3 is a vertical transverse section, on an enlarged scale, of one of the legs of the boiler. Fig. 4 is a horizontal section thereof in line 4—4, Fig. 3.

Similar letters of reference indicate corresponding parts throughout the several views.

The general construction of the boiler shown in the drawings for illustrating my invention consists of a brick shell A, a grate B arranged in the lower part of this shell above an ash pit b therein and a plurality of hollow arch-shaped water sections arranged in a longitudinal row within the upper part of the shell and each having a pair of upright legs C arranged on opposite sides of the grate and a head D connecting the upper ends of the legs. The several sections together form the furnace or fire place of the boiler above the grate and the same are in communication, so that the water can pass from one to the other.

On the inner side of each leg the same is provided with a hollow inwardly bulging part or extension E which communicates with the interior of the leg. The central or salient part of this extension is provided with a vertical row of corrugations e each of which extends in a horizontal direction. These extensions on the legs of the water sections project inwardly into the furnace or fire place and over the grate, whereby the heat rising from the burning fuel on the latter acts more effectively on the water in the boiler sections. Inasmuch as the salient portions of the extensions on the sections are exposed more directly to the heat of the furnace than its receding portions, the same are liable to expand and contract unevenly but this is permitted by reason of the corrugations on the salient parts thereof. In addition to allow-

ing for expansion and contraction on the salient part of the extension, the corrugations also increase the heating area of the same, thereby enabling the water to be heated and the steam to be generated more rapidly.

f represents an upright diaphragm or partition arranged in each extension and extending from side to side thereof, as shown in Fig. 4, but terminating at its upper and lower ends short of the top and bottom of the extension. This part separates a part of the water in the extension almost wholly from the water in the leg and confines the same in contact with the corrugated salient part of the extension, whereby this water becomes quickly heated. As the hot water rises, it passes from the bay or cut-off space within the extension over the top of the partition f into the main part of the leg and water of lower temperature passes underneath the partition into the cut-off space. By this means the heat is applied more directly to a small part of the water at a time, whereby the temperature of the same is raised more rapidly and steam is generated more quickly.

In order to further increase the heating effect of the fire on the body of water confined in the extension, an upright tube or flue G is provided. This flue is arranged in the extension between the salient part of the same and the partition and opens at its upper and lower ends through the top and bottom of the extension, as shown in Fig. 3. As the heat of the furnace passes upwardly through the flue G the water surrounding the same in the extension is rapidly heated and caused to circulate quickly. To permit the flue to expand and contract freely, so that it can adapt itself to changes in temperature and also to increase the heating area of the same, this flue is provided with circumferential corrugations g extending throughout the length thereof, as shown in Fig. 3.

My improved construction of boiler or heater causes the heat of the furnace to act more promptly and effectively on the water before the heat escapes, thereby utilizing the fuel to a greater advantage and enabling the boiler to be of service in less time than has been possible heretofore.

I claim as my invention:

1. A boiler having an upright water leg which is provided with a laterally projecting

hollow extension and an upright flue arranged in said extension and opening at its upper and lower ends through the top and bottom of said extensions.

- 5 2. A boiler having an upright water leg which is provided on its inner side with a laterally-projecting hollow extension, an upright partition arranged within said extension and terminating at its upper and lower 10 ends short of the top and bottom of said extension, and an upright flue arranged in said extension between the salient part thereof and said partition and opening at its upper and lower ends through the top and bottom 15 bottom of the extension.
3. A boiler having an upright water leg which is provided on its inner side with a lat-

erally-projecting hollow extension, an upright partition arranged within said extension and terminating at its upper and lower 20 ends short of the top and bottom of said extension, and an upright flue arranged in said extension between the salient part thereof and said partition and opening at its upper and lower ends through the top and bottom 25 of the extension, the salient part of said extension having horizontal corrugations and said flue having circumferential corrugations.

Witness my hand this 17th day of October, 1908.

MICHAEL KELLY.
